(57) **CLAIM**

The ornamental design for a split-screen display device, as shown and described.

DESCRIPTION

FIG. 1 is a front, top perspective view of a first embodiment of a split-screen display device, showing my new design; FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1; FIG. 10 is an enlarged view of detail "10" identified in FIG. 1;

FIG. 11 is another perspective view of the split-screen display device, shown in an alternate position; FIG. 12 is another perspective view of the split-screen display device, shown in an alternate position;

FIG. 13 is a front, top perspective view of a second embodiment of the split-screen display device; FIG. 14 is a rear, bottom perspective view thereof;

FIG. 15 is a front elevation view thereof;

FIG. 16 is a rear elevation view thereof;

FIG. 17 is a left side elevation view thereof;

FIG. 18 is a right side elevation view thereof;

FIG. 19 is a top plan view thereof;

FIG. 20 is a bottom plan view thereof;

FIG. 21 is an enlarged view of detail "21" identified in FIG. 13;

FIG. 22 is an enlarged view of detail "22" identified in FIG. 13;

FIG. 23 is another perspective view of the split-screen display device, shown in an alternate position; and,

FIG. 24 is another perspective view of the split-screen display device, shown in an alternate position.

The dashed broken lines in the figures illustrate portions of the split-screen display device that form no part of the claimed design. The dash-dot-dash broken lines in FIGS. 1, 13;

(Continued)

9, 10, 13, 21 and 22 depict the bounds of the enlarged views and form no part of the claimed design.
